UNITED STATES PATENT OFFICE.

FRANCIS E. KING, OF BALTIMORE, MARYLAND, ASSIGNOR TO THE KING CANDY LETTER COMPANY, OF BALTIMORE, MARYLAND, A CORPORATION OF MARYLAND.

CANDLE DECORATION.

Application filed August 30, 1924. Serial No. 735,051.

This invention relates to certain new and useful improvements in candles primarily adapted for decorating purposes and the particular object of this invention is the provision of a candle molded into various designs and shapes, such as the alphabet, figures, or the like, or can be molded into different ornamental designs, so as to create a distinctive feature of decoration.

10 The primary object of the invention is to provide a wax body molded into shapes of letters, figures, or the like, and wicks embedded in the body of the letters, figures, or the like, so that they may be ignited and display 15 the features of the molded body.

A still further object of the invention is to provide a body in which small candles may be readily set and lighted so as to bring forth the particular construction of the body be it 20 a letter or figure.

Heretofore in the decoration of cakes and similar articles, particularly for birthdays and anniversaries, it has been customary to embed in the cake candles, either spelling a 25 name or by placing sufficient candles to represent the age, and it is the purpose of my invention to overcome this particular feature by molding the candle proper into the various letters and figures, the candle proper 30 carrying its own wick, and it is then only necessary to place the candle proper upon the article to be decorated and the design is complete.

With these and other objects in view the invention consists in certain novel features, combination and arrangement of parts as will be hereinafter more fully described, pointed out in the drawing, and claimed.

In the drawing,

40 Figures 1 and 2 are perspective views of my improved candle as made in accordance with this invention,

Figure 3 is a transverse vertical sectional view showing the manner of embedding the 45 wicks in the candle,

Figure 4 is a perspective view of a modified form of the candle body showing the same adapted to receive auxiliary candles, and

Figure 5 is a transverse vertical sectional view, illustrating the modified form of the 50 auxiliary candle in position.

Referring to the drawing, the numeral 5 indicates a body of material molded to form letters, figures, or the like. This body, as shown in Figures 1, 2, and 3, is made of wax, 55 paraffin or the like, and is provided at relatively spaced distances with suitable wicks 6, which wicks are embedded in the body 5 sufficiently to permit a continuous burning until the body is consumed.

To retain the body 5 against accidental displacement from an article, a suitable securing means 7 is embedded therein. It is not necessary that this anchoring means be employed, because the article 5 can be simply retained by its own weight on the various articles upon which it is used.

It will be readily seen that by molding the various letters or figures and positioning the wicks 6 therein, that when the wicks are 60 lighted the characteristics of the particular letter or figure are very prominently brought forth.

For an illustration of the use of my device, should one want to spell the name "Mary" it 75 is only necessary to have sufficient wax letters made up into designs such as "M", "A", "R", "Y", and if "Mary" was fifteen years old it would only be necessary to use the figures "1" and "5", and as the construction 80 of each letter or figure is identical, the description of Figures 1, 2, and 3, is sufficient for all.

Now referring to the modifications shown in Figures 4 and 5. The body of the article 85 5' is made of wax or any other suitable composition, and it is provided with a suitable anchoring means 6', to retain this body on the article upon which it is used. The difference between the body 5' and 5 is that it is 90 provided on its upper surface with a plurality of relatively spaced recesses 7', in which recesses are fitted small ornamental candles 8', and as the recesses together with the candles present the same features as the wick 6, the 95 only variance in the two constructions is the

use of auxiliary candles, thus making the body 5' a holder instead of the uniform article.

Having thus described my invention, what I claim as new is:

A decoration for edible substances, comprising a body molded of candle or like composition and formed in the shape of a character, wicks projecting from the surface of such

molded body at substantially regular intervals to permit, when lighted, an illuminated outline of the molded body, and means carried by the body to permit it to be temporarily connected to the edible substance. ¹⁰

In testimony whereof he hereunto affixes ¹⁵ his signature.

FRANCIS E. KING.
